(57) **CLAIM**

The ornamental design for a control panel for appliance with embedded display screen having a graphical user interface, as shown and described.

DESCRIPTION

FIG. 1 is a front perspective view of a control panel for appliance with graphical user interface according to a first embodiment of our design;

FIG. 2 is a front view thereof;

FIG. 3 is an enlarged partial view showing the graphical user interface of the control panel for appliance with embedded display screen having a graphical user interface of FIG. 1; FIG. 4 is a front perspective view of a control panel for appliance with embedded display screen having a graphical user interface according to a second embodiment of our design;

FIG. 5 is a front view thereof;

FIG. 6 is a front perspective view of a control panel for appliance with embedded display screen having a graphical user interface according to a third embodiment of our design;

FIG. 7 is a front view thereof;

FIG. 8 is a front perspective view of a control panel for appliance with embedded display screen having a graphical user interface according to a fourth embodiment of our design; and,

FIG. 9 is a front view thereof.

The evenly spaced broken lines illustrate portions of the control panel for appliance with embedded display screen having a graphical user interface. The dash-dot-dot broken lines illustrate the boundary of the graphical user interface. None of the broken lines form part of the claimed design.
